COMBINED FRONT ORNAMENT AND EAR PIECE FOR EYEGLASSES

Robert Gross, Hackensack, N. J., assignor to Carl Schleicher, doing business as Geneva Products Company, New York, N. Y.

Application May 17, 1957, Serial No. 46,254

Term of patent 14 years

(Cl. D57—1)

Fig. 1 is a side perspective view of a combined front ornament and ear piece for eyeglasses embodying my new design; and

Fig. 2 is a front elevation thereof, parts being omitted for convenience of illustration.

The dominant features of my design reside in the portions shown in full lines.

I claim:

The ornamental design for a combined front ornament and ear piece for eyeglasses, as shown and described.
